His Attorney.

UNITED STATES PATENT OFFICE.

JAMES H. MOSHER, OF SCHENECTADY, NEW YORK, ASSIGNOR TO GENERAL ELECTRIC COMPANY, A CORPORATION OF NEW YORK.

SUPPORT FOR VACUUM TUBES.

Application filed June 2, 1926. Serial No. 113,321.

My present invention relates to supports for electric discharge devices and more particularly to a support and shielding means adapted to prevent the transmission of external vibrations to the electrodes of discharge devices.

Vibrations transmitted to a discharge device tend to change the space relation of the electrodes mounted therein. Such changes produce variations in the output of the discharge device and when the device is employed in connection with reproducing apparatus such as loud speakers and the like, seriously interfere with the operation of the reproducing apparatus and tend to make the signals reproduced thereby unintelligible.

According to the present invention, a socket adapted to support a discharge device is mounted in a standard base, or cup-shaped member, in such a way that vibrations cannot be transmitted through the socket member to the electrodes of the discharge device. Also, since discharge devices are frequently so mounted that they are not only affected by mechanical vibrations but also by sound waves emitted from loud speakers associated therewith, a shielding means is provided which completely surrounds the discharge device and is adapted to absorb any sound waves which would ordinarily be transmitted to the glass enclosure of the discharge device.

The novel features which I believe to be characteristic of my invention are set forth in the appended claims. My invention itself, however, will best be understood from reference to the following specification taken in connection with the accompanying drawing in which Fig. 1 is a cross sectional view of the support and shielding means, the discharge device being shown in elevation; Fig. 2 is an exploded view of the support and shielding means for the discharge device; while Fig. 3 is a plan view of the standard base member with the socket for the discharge device mounted therein.

Referring to the drawing, I have indicated at 1 an insulating cup-shaped member or base of standard form which is provided with four hollow terminals 2. An insulating socket member 3, which comprises upper and lower sections 4 and 5 respectively, joined together by a central rivet 6, is adapted to be mounted in the base 1. A plurality of coil

springs 7 is inserted in base 1 and supports the socket member 3 therein. Each spring is 55 electrically connected at one end to one of the hollow terminals 2 and at the other end to a metallic member 8 mounted in socket 3. A portion of each member 8 is bent outwardly, as indicated at 9, and soldered to the upper 60 portion of spring 7.

Base 1 is provided on its periphery with a plurality of relatively large openings 10 and a projecting portion 11, as indicated in Figs. 2 and 3. In the assembly of the socket and base the lower ends of the springs 7 are first soldered to the hollow terminals 2. Pins 12 are then inserted through openings 10 and driven into the lower portion 5 of the socket member 3 and thereafter serve to limit the 70 longitudinal movement of the socket member in the base 1. When a tube or discharge device 13 is inserted in socket member 3 the latter member is depressed until the pins 12 engage the lower portions of openings 10, after 75 which the tube may be firmly inserted into the socket. Likewise, when the tube is removed, pins 12 engage the upper portion of openings 10 and permit removal of the tube without causing any distortion or damage to 80 the spring supports.

While the springs or flexible supporting means 7 prevent transmission of mechanical vibrations through socket member 3 to the discharge device, vibrations from reproducing apparatus associated with the discharge device may affect its operation due to sound waves striking the glass enclosure of the discharge device. In order to absorb such vibrations a relatively thin elongated metallic cap 85 or cover 14 having depending fingers 15, is mounted on the base or cup-shaped member 1. The interior of the cap is provided with a heavy felt lining 16 which effectively prevents any transmission of vibrations to the 90 glass wall of the discharge device 13. The cap is slidably mounted upon and snugly fits the open end of the base 1, the depending fingers being so spaced as to accommodate the projecting pins 12. The projecting portion 100 11 on base 1 engages one of the openings between fingers 15 and serves as a guide for the cap 14. Any vibrations striking cap 14 are either absorbed in the felt lining or are transmitted to the base 1 and absorbed in the 105 spring supports 7. The discharge device 10

is therefore completely shielded from all forms of external vibrations, thus providing a discharge device in which the space relation of the electrodes is maintained substantially constant.

What I claim as new and desire to secure by Letters Patent of the United States, is,—

1. In combination, a cup-shaped member provided with a plurality of projecting terminals, a socket flexibly mounted in said member and adapted to support an electric discharge device, means electrically connecting said socket and terminals, and a cap mounted on the cup-shaped member and adapted to substantially enclose said electric discharge device, said cap being provided

with means adapted to substantially prevent transmission of vibrations therethrough.

2. In combination, a cup-shaped member provided with a plurality of projecting terminals, a socket flexibly mounted in said member and adapted to support an electric discharge device, means electrically connecting the socket and terminals, and a cap slidably engaging the cup-shaped member and substantially enclosing said electric device to thereby prevent the transmission of external vibrations to said device.

In witness whereof, I have hereunto set my hand this 29th day of May, 1926.

JAMES H. MOSHER.
